CLAIM

The ornamental design for an airplane beverage decanter with stand, as shown and described.

DESCRIPTION

FIG. 1 is a perspective view of an airplane decanter with stand in accordance with my new design;

FIG. 2 is a front view thereof;

FIG. 3 is a rear view thereof;

FIG. 4 is a left side view, thereof;

FIG. 5 is a right side view, thereof;

FIG. 6 is a top view; and,

FIG. 7 is a bottom view.

The portions shown in dashed lines form no part of the claimed design.

1 Claim, 6 Drawing Sheets
